FILM STRIP VIEWER

William L. Lawson, Forest Hills, and Venerio J. Rigolini,
Brooklyn, N.Y., assignors to Whitehouse Products, Inc.,
Brooklyn, N.Y.

Filed Oct. 2, 1970, Ser. No. 25,303

Term of patent 14 years

Int. Cl. D16—02

U.S. Cl. D61—1.N

FIG. 1

FIG. 2

FIG. 3

FIG. 4

FIG. 5

FIG. 6

FIG. 1 is a front elevational view of a film strip viewer showing one embodiment of our new design;

FIG. 2 is a rear elevational view thereof;

FIG. 3 is a top plan view thereof;

FIG. 4 is a bottom plan view thereof;

FIG. 5 is a right-side elevational view thereof; and

FIG. 6 is a left-side elevational view thereof.

The ornamental design for a lock on tag, substantially the enlarged and extended viewing screen and a rear film strip coiler in combination with the conventional main viewer body.

We claim:

The ornamental design for a film strip viewer, as shown and described.
